AIR VALVE FOR RADIATORS

Richard W. Shoemaker, Woodbury, Conn., and Joseph A. Parks, Jr., Rochester, N. Y., assignors to Anderson Products, Inc., Cambridge, Mass., a corporation of Massachusetts

Application July 15, 1936, Serial No. 90,760

8 Claims. (Cl. 236—61)

This invention relates to air valves for radiators of heating systems and it is an object of this invention to provide an improved device of the type described of simple construction which will be reliable in operation and in which each part is designed for the carrying out of a particular function.

In the drawing in which a preferred embodiment of this invention is shown—

Fig. 1 is a central vertical sectional view of a device constructed in accordance with this invention, the parts being shown as when subjected to atmospheric pressure and temperature;

Fig. 2 is a similar view with certain parts being shown in elevation and positioned as when subjected to steam temperature; and

Fig. 3 is a view similar to Fig. 1 of a modified construction.

An air valve constructed in accordance with this invention comprises a cylindrical or cup-shaped base member 1 open at one end and having a threaded projecting outlet 2 adapted to be screwed into a correspondingly threaded opening in a radiator section to mount the air valve thereon and to establish connection between the interiors of the radiator and air valve. Secured in the open end of the base member 1 in any suitable manner is a tubular air valve shell 4 of suitable light metal, and closed at its upper end except for a port or opening 6 therein.

Located in the base member 1 is a cell 8 having a rigid radially corrugated bottom 9, a rigid cylindrical side wall 10 and a top wall or closure formed of a diaphragm which may be either of the snap or flexible diaphragm type. In the structure shown in Figs. 1 and 2, the diaphragm 11 is arranged to assume a position in which its outer face is concave as shown in Fig. 1 except when the difference in the forces or pressures acting upon opposite sides of the diaphragm is sufficient to force the diaphragm outwardly and hold it in the position shown in Fig. 2, while in the modified construction shown in Fig. 3 the diaphragm 11^a is arranged to assume a position in which its outer face is convex, as shown in Fig. 3 except when the difference in the pressures or forces acting upon opposite sides thereof is sufficient to hold it with its outer face concave.

Extending from the cell bottom 9 is a tube 12 which establishes communication between the interior of the cell 8 and the atmosphere and which is threaded through an opening in the bottom of the base member 1 so the cell 8 may be adjustably positioned in the casing formed of

the base 1 and the shell 4. A lock nut 14 on the tube 12 secures the cell in adjusted position.

Enclosed within the cell 8 is a double diaphragm thermostatic element 16 formed of a ring 17 and diaphragms 18 and containing a suitable volatile liquid, as a mixture of alcohol and water. The diaphragms 18 of the thermostatic element are arranged to present concave outer faces as shown in Figs. 1 and 3 unless forced or held outwardly as in Fig. 2.

Supported on the diaphragm 11 or 11^a of the cell 8 is a hollow float member 20 having a projecting pin or valve 22 at its upper end arranged to seat in the opening or port 6 to prevent the escape of fluid therefrom. The parts of the structure shown in Figs. 1 and 2 are so proportioned and adjusted that when diaphragm 11 is subjected to atmospheric pressure on opposite sides and the thermostatic element 16 is not expanded, the valve 22 opens the port 6 to a greater or less extent depending upon the adjustment of the tube 12 in the base member 1 but the float 20 and valve 22 are always so positioned that movement of the diaphragm 11 will be sufficient to seat valve 22 in the port 6 and close the port. In the structure shown in Fig. 3 when the diaphragm 11^a is subjected to atmospheric pressure on opposite sides the float 20 and valve 22 are held in position to close the port 6.

With the parts of the structure shown in Figs. 1 and 2 positioned as in Fig. 1 passage of steam to the system causes the air to be forced out through port 6, the valve 22 remaining withdrawn from the port 6 until the steam acting upon the thermostatic element 16 through the walls of the cell 8 raises the temperature of the liquid in the element 16 sufficiently to volatilize part of the liquid and force out the diaphragms 18 to the positions shown in Fig. 2. This movement of the diaphragms 18 operates the diaphragm 11 and the float member 20 causing valve 22 to close the port 6. Should there be sufficient condensation to fill the casing before the element 16 is expanded the float 20 is raised by the liquid in the casing, closing port 6 and preventing escape of the liquid.

Upon the shutting off of steam from the system and the reduction of the temperature therein the thermostatic element 16 resumes the condition shown in Fig. 1 but the reduced pressure in the valve casing, less than atmospheric pressure at this time, causes the diaphragm 11 to be held in the position shown in Fig. 2 by the atmospheric pressure within the cell 8 until the

pressures on opposite sides of the diaphragm 11 are equalized either by leakage of air into the system or by the operation of a vacuum breaking device which is operated upon reduction of the pressure and temperature in the system to admit air thereto so as to place the valves at the radiators in condition to vent air during a subsequent heating of the system.

With the parts of the structure shown in Fig. 10 3 positioned as shown in that figure, passage of steam to the heating system causes air pressure to be built up in the valve casing until the difference in the pressures on the opposite sides of the diaphragm 11^a, the inner face thereof being 15 subjected to atmospheric pressure, is sufficient to force the diaphragm 11^a inwardly, permitting the float 20 to fall and causing the valve 22 to open the port 6. At this time the parts have the same relative positions as the parts of the structure shown in Fig. 1 and these positions are maintained while the difference in the pressures on the opposite sides of the diaphragm 11^a is maintained as the steam raises the temperature of the volatile liquid in the thermostatic element 16 sufficiently to volatilize some of the liquid 20 therein and force the diaphragms 18 outwardly, causing the diaphragm 11^a to be returned to the position shown in Fig. 3 and the float 20 and valve 22 raised to close the port 6. The parts of 25 the device are then in the positions shown in Fig. 2. If there is sufficient condensation to fill the valve casing before the element 16 is expanded, the liquid will raise the float 20 and valve 22 to close the port 6.

Upon the shutting off of steam from the system 30 and the reduction of the temperature therein the thermostatic element 16 resumes the condition shown in Fig. 3 while the diaphragm 11^a remains in the outwardly flexed condition shown in that figure and maintains valve 22 closed, at first because of the reduced pressure, less than atmospheric, then existing in the valve casing and, after the restoration of atmospheric pressure in the heating system, because the diaphragm 11^a 35 is arranged to maintain that position when subjected to equal pressures on opposite sides thereof. In this arrangement, the diaphragm 11^a, being arranged to hold the valve 22 closed when subjected to equal pressures on opposite sides 40 thereof, closes the valve 22 upon the reduction of pressure in the system at such times as the steam is shut off from the system before the steam heats the radiator throughout and raises the temperature of the liquid in the thermostatic element 16 so that the valve 22 prevents the admission of air to the system irrespective of 45 whether or not the thermostatic element 16 is heated.

What is claimed is:

60 1. In an air valve for radiators, a casing having a vent port and an inlet port, a cell in said casing having a movable wall, means establishing communication between the interior of said cell and the atmosphere, a thermostatic element in said cell and exposed to the atmosphere for operating the wall upon application of heat to said element, a float supported by said wall and a valve on said float for closing said vent port upon operation of said wall by said thermostatic element.

2. In an air valve for radiators, a casing having a vent port and an inlet port, a cell in said casing having a movable wall, means adjustably supporting said cell in said casing, said means establishing communication between the interior of said cell and the atmosphere, a thermostatic element in said cell and exposed to the atmosphere for operating the wall upon application of heat to said element, a float supported by said wall and a valve on said float for closing said vent port upon operation of said wall by said thermostatic element. 5

3. In an air valve for radiators, a casing having a vent port and an inlet port, a cell vented to the atmosphere in said casing having a movable wall, means adjustably supporting said cell in said casing, a hollow sealed thermostatic element in said cell for operating said wall upon application of heat to said element, a hollow sealed float supported on said wall and a valve on said float for closing said vent port upon operation of said wall by said thermostatic element. 10 15

20

4. In an air valve for radiators, a casing having a vent port and an inlet port, a valve adapted to close the vent port, a flexible wall supporting said valve, a cup-shaped support for said wall forming therewith a cell, a thermostatic element in said cell of substantially less volume than the volume of said cell to provide an insulating space between said cell and thermostatic element, tubular supporting means for said cell, said supporting means establishing communication between the atmosphere and the interior of said cell, the bottom of said cell acting as a support to cause movement of said wall and valve upon operation of said thermostatic element. 25 30 35

5. In an air valve for radiators, the combination set forth in claim 4 and in which the valve is mounted on a float intermediate said vent port and said flexible wall. 40

6. In an air valve for radiators, a casing having a vent port and an inlet port, a valve adapted to close the vent port, a cell in the casing, said cell having a flexible upper wall and associated with the valve, a thermostatic element in said cell of substantially less volume than the volume of said cell to provide an insulating space therebetween and acting between the bottom of said cell and said flexible upper wall for closing said valve upon the application of heat, and means supporting said cell and admitting the atmosphere to the interior thereof. 45 50 55

7. In an air valve for radiators, the combination set forth in claim 6 and in which the valve is mounted on a float intermediate said vent port and said flexible upper wall. 55

8. In an air valve for radiators, a casing having a vent port and an inlet port, a valve to close said vent port, a cell closed with respect to said casing and fixed therein, a thermostatic element positioned inside the fixed cell, and effectively spaced from the sides of said cell, thereby being insulated from the casing temperature, and means for transmitting the action of said thermostatic element to the valve. 60 65
